Primary Examiner — Selina Sikder(74) *Attorney, Agent, or Firm* — SAIDMAN DesignLaw Group(57) **CLAIM**

The ornamental design for a fan component, as shown and described.

DESCRIPTION

FIG. 1 is a perspective view of a fan component showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines illustrate environmental structure and form no part of the claimed design.

1 Claim, 5 Drawing Sheets(56)
